UNITED STATES PATENT OFFICE,

LEWIS ELLIOTT, OF NEW HAVEN, CONNECTICUT, ASSIGNOR TO L. CANDEE
& CO., OF SAME PLACE.

DESIGN FOR THE ORNAMENTATION OF INDIA-RUBBER SOLES.

SPECIFICATION forming part of Design No. 16,018, dated April 7, 1885.

Application filed March 9, 1885. Term of patent 14 years.

To all whom it may concern:

Be it known that I, LEWIS ELLIOTT, of New Haven, in the county of New Haven and State of Connecticut, have invented and produced a Design for India-Rubber Soles; and I do hereby declare the following, when taken in connection with accompanying drawings and the letters of reference marked thereon, to be a full, clear, and exact description of the same, and which said drawings constitute part of this specification, and represent, in—

This invention relates to a design for the roughening of the surface of the sole of india-rubber boots and shoes, whereby that surface is made highly ornamental; and it consists in the ornamentation as shown in the accompanying illustration and hereinafter described. The ornamentation consists of two series of ribs crossing each other, forming diamond-shaped panels on the sole. The surface of these panels is cut in the form of lozenge-shaped figures, as shown.

I claim—

The design for the ornamentation of the soles of india-rubber boots and shoes, consisting in the two series of ribs crossing each other, forming diamond-shaped panels on the sole, the surface of the said panels presenting lozenge-shaped figures, as shown and described.

LEWIS ELLIOTT.
